UNITED STATES PATENT OFFICE.

ALFRED ROWE BELLAMY, OF STOCKPORT, ENGLAND.

INTERNAL-COMBUSTION ENGINE.

No. 855,611.

Specification of Letters Patent.

Patented June 4, 1907.

Application filed April 3, 1907. Serial No. 366,143.

To all whom it may concern.

Be it known that I, ALFRED ROWE BELLAMY, a subject of Great Britain, residing at Fordsburg, Edgeley, Stockport, in the county 5 of Chester, England, engineer, have invented new and useful Improvements in or Connected with Internal-Combustion Engines, of which the following is a specification.

My invention has reference to internal 10 combustion engines and relates to means for controlling the lift of the valve by which more or less gas or explosive mixture is admitted to the engine cylinder.

The mechanism I have invented for this 15 purpose is illustrated in the accompanying two sheets of drawings in which:—

Figure 1 shows in end view, partly in section, so much of an internal combustion engine as is necessary to illustrate my invention. Fig. 2 is a view at right-angles thereto, and Figs. 3 to 5 are detail views.

In the accompanying drawings A represents the governor, which is of the usual or well-known type, and to the rocking shaft *a* thereof I secure a rod *b* to which is attached a projection or part *c* having a wedge shaped or inclined surface *d*. The part *c* is shown in plan view in Figs. 3^a, 4^a and 5^a. The tripper lever *f* carrying the blade *e* is carried as usual 20 on a stud by the plunger *f'* actuated by the pivoted lever *e'* from the side shaft *e*² in the ordinary manner. I arrange that the tripper blade *e* shall bear by means of a spring *g*, or it might be a load, against such inclined 25 surface *d*. The motion of the governor rocking shaft *a* imparts movement to the part *c* having the inclined surface *d*, and when such inclined surface is thus moved, the tripper blade *e*, being constantly maintained against 30 the incline by the spring or load, is turned on its pivot and necessarily varies its direction of movement to some degree with relation to the stem *h* whereby the gas or charging valve *i* is actuated. In the drawings (Fig. 2) it 35 will be seen that the stem *h* operates the gas valve *i* through the medium of a bell-crank lever *i'*. I provide the stem *h* actuating the gas valve, or other valve which it is desired 40 to operate, with a stepped contact piece *j* the various steps receding from the point of the tripper blade as shown clearly in Figs. 1, 3 and 4.

As will be understood the nearer the step to the tripper blade *e* with which the blade

comes into contact, the sooner will the valve 55 be opened and the longer maintained open to admit the gas or charge of explosive mixture. Such a stepped contact piece *j* working in conjunction with a tripper blade, I do not however claim to be new, the essential novel 60 feature of my invention being to arrange that the tripper blade shall always be held in contact with an inclined surface such as *d* actuated through the governor rocking shaft.

At the maximum load on the engine the 65 part *c* with inclined surface *d* is moved by the governor rocking shaft *a* to turn the tripper lever on its fulcrum so as to direct the tripper blade *e* against the step on the gas or other valve stem nearest to the tripper blade and 70 so open the valve for the maximum period of time. This is shown by Figs. 3 and 3^a of the drawings. On a diminishing load the tripper blade comes into contact with the next step, as shown in Fig. 1, the position of 75 the part *c* relative to the tripper blade being as indicated in plan view in Fig. 5, and so on from a maximum to a minimum, or to an entire "miss" of the stem *h* as shown in Figs. 4 and 4^a when the gas or other valve is not to 80 be opened as will be understood.

Figs. 3^a and 4^a show in plan view the tripper blade *e* and the wedge shaped part *c*.

An important advantage of my invention lies in the fact that the variable lift of the gas 85 or other valve is effected by a comparatively light strain on the governor, as the only work to be done is the sliding of the part *c* provided with the wedge or inclined surface *d* against the spring actuated or loaded tripper 90 blade *e*. The friction of these parts may also be reduced by providing a rounded contact surface on the tripper blade *e* as illustrated, or in other convenient ways. Thus it is not necessary to provide a special strong heavy 95 governor, but the light governor usually employed with combustion engines is sufficient for the requirements.

I declare that what I claim is.

1. In internal combustion engines a rod *b* 100 connected to the rock-shaft of the governor, a part *c* attached to such rod and formed with an inclined surface, a tripper blade and means to maintain such tripper blade against the inclined surface substantially as described. 105

2. The combination in internal combustion engines of the plunger *f'*, a tripper lever and blade carried by the plunger, means for ac-

tuating the plunger, a governor, a governor
rocking shaft, a rod carried by the governor
rocking shaft, a part *c* attached to the rod
having an inclined surface, means to main-
5 tain the tripper blade against such inclined
surface, and a stepped contact piece on the
valve stem substantially as described.

In testimony whereof I have signed my
name to this specification in the presence of
two subscribing witnesses.

ALFRED ROWE BELLAMY.
